(57) CLAIM

The ornamental design for a two-piece swimsuit, as shown and described.

DESCRIPTION

FIG. 1 is a front view of a two-piece swimsuit showing the new design.

FIG. 2 is a rear view thereof.

FIG. 3 is a right side view thereof.

FIG. 4 is a left side view thereof.

FIG. 5 is a front view of a second embodiment of a two-piece swimsuit showing the new design.

FIG. 6 is a rear view thereof.

FIG. 7 is a right side view thereof; and,

FIG. 8 is a left side view thereof.

The surface stipplings of FIGS. 5-8 are provided to show color contrasts with the remainder of the swimsuit.

The broken lines in FIGS. 1-8 showing a portion of a human body are for the purpose of illustrating the environment of use and form no part of the claimed design.
